J. T. HORTON,
SECTIONAL BOOM,
APPLICATION FILED APR. 23, 1920.

Patented Jan. 18, 1921.

Inventor,
John T. Horton;
By Wilbur M. Stone
his Attorney.

UNITED STATES PATENT OFFICE.

JOHN T. HORTON, OF BROOKLYN, NEW YORK.

SECTIONAL BOOM.

1,365,998.

Specification of Letters Patent. Patented Jan. 18, 1921.

Application filed April 23, 1920. Serial No. 375,948.

To all whom it may concern:

Be it known that I, JOHN T. HORTON, a citizen of the United States, and a resident of New York, borough of Brooklyn, in the county of Kings and State of New York, have invented certain new and useful Improvements in Sectional Booms, of which the following is a specification.

This invention relates to sectional booms and has for its object to provide a structure of the class specified of simple and rigid construction, and which may be formed of relatively short members. With these objects in view and others which will appear later herein my improvements comprise features which are illustrated in their preferred embodiment in the drawings accompanying this specification, wherein:

Figure 1 is a front elevation of my improved sectional boom in its assembled condition. Fig. 2 is a similar view with portions near either end broken out. Fig. 3 is a front elevation of a portion of one end member separated from the remaining portions of the boom. Fig. 4 is a front elevation of a portion of one end member and the central core member assembled. Fig. 5 is an end elevation looking toward the right in Fig. 4. Fig. 6 is an end elevation looking toward the left in Fig. 3. Fig. 7 is an end elevation of the central core member. Fig. 8 is an end elevation corresponding with Fig. 2. The scale of Figs. 2 to 8 inclusive is the same and the scale of Fig. 1 is about one half that of the other figures.

When booms or other spars are formed of one piece of wood, they are open to the objection of unnecessary weight and undue cost. Also, if built up of two or more members running the full length of the boom, in many cases the length of the boom is objectionable and cumbersome in shipping. Also, the present cost of long timbers is excessive. With my improvements, not only can a boom be constructed much lighter than as if made of one piece, but much more convenient, under many circumstances, than as if made of a plurality of pieces of substantially the full length of the boom.

My improved boom comprises a central core member 2 of cruciform cross-section having seats, as 3, in each of its corners for the reception of the four timbers as 6, 7, 8 and 9, respectively, comprising each of the end members 4, 5 of the boom. Said core member is of sufficient length to provide

adequate seats for said corner timbers and adequate lengthwise spacing for the holding bolts as 10, 11. End member 4 may be provided with a spacing member 16 of cruciform shape for holding the inner ends, respectively, of timbers 6, 7, 8 and 9 in suitable relation to each other and to core member 2, with which said timbers engage when the boom is assembled. Said member 16 may be secured to timbers 6, 7, 8 and 9 by some convenient means not shown. The several members of my improved boom may be secured together by suitable bolts, as said bolts 10, 11, and in some cases reinforcing plates, as 17, 18, may be employed for the bolt heads and nuts to pull against and to generally strengthen the joint portion of the structure. A further important feature of my improved boom is the key pins, as 19, 20, which are efficient to prevent the corner timbers from moving endwise relatively to core member 2 when the assembled boom is subjected to bending strains. These key pins lie in opposite semi-cylindrical seats as 21 in timber 6 and 22 in the opposite arm portions of core member 2, said seat 22 being fully cylindrical where it passes through the central portion of said core member.

The timbers at the outer extremities of end members 4, 5, respectively, of the boom are brought together to form a four-part square end, see Fig. 8, and are secured together by bolts as 23, 24. Said ends are also provided with key pins 25, 26 to prevent endwise movement of timbers 6, 7, 8 and 9 relatively to each other at those ends.

Also said key pins are arranged in pairs or sets having pins at right angles to each other, as pins 25, 26 of the pair at one end of the boom, and set 27, 28, 29 and 30 near the middle of the boom, wherein pins 27, 28 are at right angles to pins 29, 30. By this arrangement the several lengthwise timbers are prevented from relative lengthwise movement against bending stress from any transverse direction.

Preferably the timbers of one of the boom ends, as 5, are first assembled on core member 2 by bolts and key pins as shown, said timbers overlapping said core member about half its length. Then the other end 4 is thrust endwise into engagement with core member 2, the several corner timbers of said end 4 sliding into their respective seats 3 in said core member. Then the bolts as 10, 11 are put into place and their nuts

screwed on, and the key pins as 19, 20 are driven into place thereby securing the opposite end members 4, 5 and the central core member 2 into one relatively light but rigid structure.

While I have described my improved device as built of "timbers", that is, wood, it will be understood that I do not limit myself to any particular material as said "timbers" may be formed from metal or other convenient material. Therefore the term timber as used herein will be understood to include members of the general character described irrespective of the material of which they are made.

It is realized that the broad proposition of a post or spar having four corner members spaced apart midway their lengths by a cruciform member and the corner members brought together at their ends, respectively, has long been known, and no claim is made to such known construction.

What I do claim is:—

1. A sectional boom comprising a pair of opposite end members, each of said end members comprising a plurality of lengthwise timbers, a central core member, and means for detachably securing the end members and the core together.
2. A sectional boom comprising a pair of opposite end members each comprising four lengthwise timbers, a central cruciform core member having seats, and means for detachably securing the timbers of said end members in the core member seats, respectively.
3. A sectional boom comprising a pair of

opposite end members, each of said end members comprising a plurality of lengthwise timbers, a central core member, means for detachably securing said end members and core together, and means in coengagement with an end member and with the core for preventing relative endwise movement of said end member and core member.

4. A sectional boom comprising a pair of opposite end members each comprising four lengthwise timbers, a central cruciform core member having seats, means for detachably securing the timbers of said end members in the core member seats, respectively, and a set of key pins comprising two pairs of pins, the members of each pair being disposed at right angles to the members of the other pair and each pin being in coengagement with two timbers and with the core member for preventing relative endwise movement of said end members and core member.

5. In a sectional boom having an end member comprising four timbers brought together to form a four part square end, the combination of means for holding said four timbers together at the end of said end member and a pair of key pins disposed at right angles to each other, each pin being seated for one half its circumference in one timber and for one half its circumference in an adjacent timber for preventing said timbers from moving endwise relatively to each other.

In witness whereof, I hereby affix my signature this 22 day of April, 1920.

JOHN T. HORTON.
